UNITED STATES PATENT OFFICE.

HILDA M. FORSSBERG, OF BROOKLYN, NEW YORK.

MANUAL TOOL.

Application filed October 3, 1921. Serial No. 504,915.

To all whom it may concern:

Be it known that I, HILDA M. FORSSBERG, a citizen of the United States, and a resident of 5 618^a Bergen Street, Brooklyn, in the county of Kings and State of New York, have invented certain new and useful Improvements in Manual Tools, of which the following is a specification.

This invention relates to general utility 10 tools of the class including weeders, scrapers and scoops, but especially to that class wherein a preferred straight sided scoop is provided with an arcuate projecting nose terminating in a straight edge or a straight 15 row of teeth.

The main object of this invention is to provide a tool of the mentioned character which is adapted to be used primarily as a 20 convenient coal saver and sifter, and secondarily as a berry picker and also a garden weeder.

Other advantages and objects attained will become apparent as this specification proceeds.

25 In the accompanying drawing—

Fig. 1 is a view of a tool embodying the present invention.

Fig. 2 is a side view of Fig. 1.

Fig. 3 is a reverse view of Fig. 1 with 30 slight modifications.

Fig. 4 is a modification of Fig. 1.

Fig. 5 is a sectional view of Fig. 2 on line 10—11.

There is a great need for a substitute 35 for the human hand when recovering half burned coals in common kitchen stoves. It is with this end in view as well as the other objects mentioned, that the present invention has been designed. Incidentally the 40 invention contemplates forming the tool so that it may be easily cast or stamped in large quantities and furthermore be graceful and convenient to use.

Returning to the drawing, the tool plate 45 or back 1 is rearwardly formed into a handle 4 having a hole 5 by which the tool may be hung up out of the way, and forwardly into a series of arcuate fingers 3, 3, 3, terminating in tips 3', 3', 3'. The sides of the 50 back 1 are formed into a pair of opposite parallel and relatively straight thumbs 6, 6' the so called fingers and thumbs being separated by spaces as at 2. The fingers 3, 3, 3

are not only arcuate in their longitudinal form, but are also arched in their transverse arrangement, in fact the whole tool is transversely arched throughout its entire length with the exception of the so called finger tips 3', 3', 3'.

However, when making the tool out of a sheet stamping, the fingers are somewhat flexible, whereas rigidity is a desideratum. In order then to properly reinforce the fingers, several slight modifications in the form of webs as at 9 may unite the fingers, leaving closed slots 2', or larger webs as indicated at 8, and 8' may together with smaller webs 7, 7 completely obscure the appearance of the fingers.

This will leave a plurality of perforations 70 or apertures 7', 7', but will not alter the shape or usefulness of the tool in any degree, especially not for coal salving.

When used for the latter purpose, the nose or tips 3', 3', 3', of the fingers may first be 75 forced down among the coals, and, with a steady drawing movement, the handle may be turned over, rolling the implement on its back in a plane in line with its fingers. If it is then lifted and lightly shaken from side 80 to side all loose ashes and dirt will sift between the fingers, and the coals may subsequently be picked off.

It may be noted in regard to the fingers' tips, that whether they are divided, or all 85 united, to form a common straight edged nose, the result is still that the main bowl portion is slotted or perforate.

Having thus fully described my invention, I claim.

1. A manual tool comprising in combination a handle having a series of arcuate fingers projecting therefrom to form a scoop, with a pair of opposite relatively straight fingers projecting on either side of said arcuate fingers from said handle to a point on the outermost of said arcuate fingers with in their free extremities.

2. A manual tool comprising a handle provided with a series of arcuate fingers 100 projecting therefrom to form a slotted scoop, a pair of opposite and relatively straight fingers projecting from the sides of said handle and joined at their forward extremities to the adjacent arcuate fingers at points 105 within the extremities of the latter, and re-

inforcing webs between all said arcuate fingers.

3. A manual tool comprising in combination a perforate bowl provided at one extremity with a handle and at the other extremity with a series of forwardly projecting fingers continuing the arcuate form of said bowl.

Signed at 686 Washington Ave., Brooklyn, N. Y., in the borough of Brooklyn, county of Kings, city and State of New York, this 1st day of October, 1920.

HILDA M. FORSSBERG.
